(57) **CLAIM**

The ornamental design for a display screen with animated graphical user interface, as shown and described.

DESCRIPTION

FIG. 1 is a front view of a first image of a first embodiment of a display screen with animated graphical user interface; FIG. 2 is a front view of a second image thereof; FIG. 3 is a front view of a third image thereof; FIG. 4 is a front view of a first image of a second embodiment of a display screen with animated graphical user interface; FIG. 5 is a front view of a second image thereof; FIG. 6 is a front view of a third image thereof; FIG. 7 is a front view of a first image of a third embodiment of a display screen with animated graphical user interface; FIG. 8 is a front view of a second image thereof; FIG. 9 is a front view of a third image thereof; FIG. 10 is a front view of a first image of a fourth embodiment of a display screen with animated graphical user interface; FIG. 11 is a front view of a second image thereof; and, FIG. 12 is a front view of a third image thereof.

The broken lines illustrating various features of the display screen with animated graphical user interface form no part of the claimed design.

The appearance of the transitional image sequentially transitions between the images shown in FIGS. 1-3, 4-6, 7-9 and 10-12. The process or period in which one image transitions to another image forms no part of the claimed design.

The broken lines illustrating various features of the display screen with animated graphical user interface form no part of the claimed design.
